Patented Oct. 24, 1922.

Fig. 5.

UNITED STATES PATENT OFFICE.

PAUL O. HOHBERG, OF BROOKLYN, NEW YORK, ASSIGNOR TO HARRY SALPETER, OF NEW YORK, N. Y.

CAN OPENER.

Application filed June 20, 1921. Serial No. 479,092.

To all whom it may concern:

Be it known that I, PAUL O. HOHBERG, a subject of Germany, and resident of 153 Prospect Ave., Brooklyn, in the county of Kings and State of New York, have invented certain new and useful Improvements in Can Openers, of which the following is a specification.

This invention relates to can openers in general and particularly to the kind whereby the cover of a can is opened at the edge thereof.

The primary object of my invention is to provide a device of this kind by means of which a can may be opened without necessitating the device being centered.

Another object of my invention is to provide in connection with such a device, means whereby the cutting member is automatically guided at the edge of the can top, no matter of what shape the top may be.

Another object of my invention is to provide in connection with such a device, sliding and self-adjusting means carrying the cutting blade which permits the unrestricted operation of the blade at the inner edge of any can.

The foregoing and still further objects will be more fully apparent from the following description, and the accompanying drawing, forming part of this specification, and in which:

Fig. 1 is a perspective view of a cylindrical can, showing my device in operation.

Fig. 2 represents my device designed for left handed operators.

Fig. 3 is a detail view of my cutting device.

Fig. 4 is a modified form thereof.

Fig. 5 is a top view of my device in modified form, shown in operation upon a square can.

I am aware of the existence of numerous devices of similar design, but of considerably different construction. As a rule, the guiding mechanisms of can openers now in use are not only slidably associated with the handle, but also prevented from any swiveling or pivoting movement, which movement becomes necessary when it is desired to cut the can exactly at the edge without requiring that the fulcrum of operation formed by the pointed end of the can opener to be in the center of the can.

Referring to the drawings, numeral 10

represents the handle of my device, in which is firmly held a flattened bar 11, having at its free end an angularly shaped point 12 which is adapted to engage the can cover proper 13 at any desired point. 60

Slidably and pivotably mounted upon the flattened bar 11 is a carriage 14 which embraces rod 11 at three of its faces. The open portion of the carriage extends outwardly at the upper face as indicated at 15 65 for receiving a rivet 16, which passes through the lower extension 17 of the carriage.

Between the upper and lower part of the carriage a small roller indicated at 18 is 70 preferably provided for spacing the carriage at its open end. The lower portion 17 extends into an arm 19 or 19' (Fig. 4) which is turned downward as shown and is adapted to guide the carriage at the outside of the 75 can top.

The cutting blade of my device may form an integral part of the carriage as shown in Figs. 2 and 3 at 20, or may be set into the carriage material as indicated at 20' in 80 Fig. 4.

The blade is offset relative to arm 19 or 19' so that when the carriage is placed upon the can, the blade engages the can edge at 85 its inner surface, while the arm glides at its outer face.

Rivet 16 and roller 18 serve two purposes. Firstly, they provide a thrust point for the bar 11 during the cutting operation, and secondly, they facilitate the rolling or self-adjustment of the carriage relative to the bar when the carriage follows the edge of the can. 90

While I have shown in Figs. 1, 2, 3, and 4, a particular design of my carriage, it might 95 be advantageous in order to provide freer movements of the carriage relative to bar 11 and the can edge, to cut out the carriage portion facing pin 12, as indicated at 21. It will also be seen in Fig. 5 that sufficient 100 free space 22 is left between the closed part 23 of the carriage and rod 11.

The operation of my device is similar to that of like devices with the difference that it becomes unnecessary to engage the center of the can by pin 12. After having pierced the can by pin 12 at any point of the can top, the blade 20 is set at the inner face of the can edge, while 19 abuts with the outer edge of the can. Now the handle is turned 110

in the direction of the lower extension 17 of the carriage, causing the blade to cut a strip of metal from out of the can cover as indicated at 24.

5 The cutting edge of the blade is square as shown at 25, so that my device works in a similar manner as would a lathe tool. Due to the construction of the carriage, it is permitted to slide or glide upon 10 rod 11, while following the outer edge of the can.

The cut made by my tool is at the extreme inner edge of the can cover, thus the entire contents of the can may be readily emptied 15 without necessitating the forcible removal of the contents, which is usually due to the incomplete cutting of the cover by tools used heretofore.

20 Due to my construction, it is not only unnecessary to pierce the center of the can with pin 12, but it is obvious that my can opener may be used for cans of various shapes, not exactly round, as for instance sardine cans which are generally rectangular, or cans of 25 oval or other shapes which may be easily opened with my device.

While I have shown a particular construction of my invention, be it understood that its working method is the main object of my 30 invention, and I do not wish to restrict myself to the particular design shown, and I therefore reserve for myself the right to

make such changes and improvements within the scope of my invention to meet various conditions arising from the different uses 35 to which my device may be put. Having thus described my invention, I claim:—

1. In a can opener, a carriage having a cutting blade, an arm spaced from said cutting blade, a pin passing through and closing said carriage and serving as pivot for the latter, a handle adapted to engage said pin during the cutting operation, said carriage adapted to slide upon said handle while automatically following the edge of 45 a can.

2. In a can opener, a handle provided with a piercing or anchoring member, a carriage slidably and swivably mounted on said handle, a blade associated with said carriage for cutting out a strip from the top of a can, said carriage having an extension for engaging the outer face of a can edge, said blade adapted to travel at the inner side of a can edge, a fastening or closing member 50 passing through said carriage and adapted to serve as a pivot for the latter, said handle adapted to engage said fastening member when the can top is to be cut.

Signed at New York, in the county of New 60 York and State of New York, this 14 day of June A. D. 1921.

PAUL O. HOHBERG.
